United States Patent Office.

G. A. RIEDEL, OF PHILADELPHIA, PENNSYLVANIA, ASSIGNOR TO THE AUTOMATIC BOILER-FEEDER COMPANY, OF PENNSYLVANIA.

Letters Patent No. 66,993, dated July 23, 1867; antedated July 9, 1867.

IMPROVEMENT IN AUTOMATIC BOILER-FEEDERS.

The Schedule referred to in these Letters Patent and making part of the same.

TO ALL WHOM IT MAY CONCERN:

Be it known that I, G. A. RIEDEL, of Philadelphia, Pennsylvania, have invented certain Improvements in Feed-Water Apparatus; and I do hereby declare the following to be a full, clear, and exact description of the same, reference being had to the accompanying drawing, and to the letters of reference marked thereon.

My invention consists of certain improvements, described hereafter, in feed-water apparatus, for which Letters Patent were granted to me on the 3d day of July, 1866.

In order to enable others to make and use my invention, I will now proceed to describe its construction and operation, reference being had to the accompanying drawing, which forms a part of this specification, and in which—

Figure 1 is a side elevation of my improved apparatus for feeding water to steam-boilers.

Figure 2, a sectional elevation.

Figure 3, a plan view of fig. 1.

Figure 4, an inverted plan view of part of the apparatus; and

Figure 5, a plan view of part of the apparatus.

To a curved seat in a pedestal or standard, B, secured to a base-plate, A, is fitted a cylindrical valve, C, the ends of which project beyond the sides of the pedestal. To the pedestal A is secured a cap D, and in a chamber or opening, α , in the centre of this cap, fits snugly, but so as to slide freely, a cylindrical plunger, E, which is pointed at its lower end, and bears against a cavity in the valve C at a point exactly in the centre of the latter, and round the plunger is coiled a spring, b , which is confined between the under side of the cap B and a collar, a , on the said plunger. Across the opening α extends a flexible diaphragm, c , the under side of which is directly in contact with the upper end of the plunger E. To one end of the valve C are connected two pipes, F F', and to the opposite end are connected two pipes, G G', the pipes F G being connected to and communicating with a metal reservoir, H, and the pipes F' G' communicating with and being secured to a similar reservoir, H'. The pipes F F' extend into the reservoirs, and nearly to the tops of the same, and at the upper end of each reservoir is a valve-cock, I. In the pedestal B is an opening, f , communicating with the boiler at the water line of the same, and with the chamber α communicates a steam pipe, which also communicates with the boiler. In the pedestal B are openings e e' , communicating with water-supply pipes or reservoirs, and an opening, d , communicating with the steam-space of the boiler, and in the valve C are ports i i' and n n' , the former communicating with the pipes G G', and the latter with the pipes F F'. The various openings and ports are so situated in the pedestal and in the valve, that each of the ports n n' will, during a portion of the operation of the machine, communicate with the opening d , while each of the ports i i' will, during a portion of the operation of the machine, communicate with either the opening f or with one of the openings e e' . The pipes F F' G G' are connected to the valve C at such an angle to each other that when one of the reservoirs is in a vertical position, it will be at the limit of its downward motion, and the other will be elevated, and inclined at an angle of about thirty degrees. To the base-plate A, beneath each reservoir, is jointed a cylinder, s , in which a hollow plunger, p , has a limited sliding motion, and through a cap at the upper end of the plunger p passes a rod, h , which is jointed at the upper end to the adjacent reservoir, and has at its lower end an enlargement or piston o .

When the apparatus is in the position shown in fig. 1, the water passes through the opening e , port i , and pipe G into the reservoir H, and out of the reservoir H' through the pipe G', port i' , and opening f to the boiler, the steam passing into the reservoir H', from the opening d , through the port n' and pipe F'. So long as there is any water in the reservoir H', its weight, with that of the reservoir itself, will counterbalance that of the reservoir H and the water with which it is partially filled. When, however, the reservoir H is nearly full, and the reservoir H' empty or nearly empty, the former reservoir will descend until the reservoirs are level with each other, when all the ports or communications will be closed, as shown in fig. 2. If the reservoirs were parallel to each other, instead of being inclined, they would now remain in the position shown in fig. 1. Owing to the angle at which the reservoirs are placed, however, the reservoir H, as it descends, is carried farther from the vertical line y y , in which is the centre of vibration, while the reservoir H' is brought nearer this line. The leverage of the reservoir H, therefore, constantly increases as the reservoir descends, so that, before reaching

the position shown in fig. 1, it more than counterbalances the weight of the reservoir H', and is carried downwards until the ports *i i'* and *n* communicate with the openings *f e' d*. The water will now pass to the boiler from the reservoir H through the pipe G, port *i*, and opening *f*, and will pass to the reservoir H' through the opening *e'*, port *i'*, and pipe G', the steam passing to the reservoir H through the opening *d*, port *n*, and pipe F. As the manner in which the water is introduced into the reservoirs and discharged into the boiler is very similar in this apparatus to the manner in which the same operations are effected in the apparatus for which Letters Patent of the United States were granted to me on the 3d day of July, 1866, further allusion to it will be unnecessary. Each reservoir moves freely at the commencement of its descent, but it is retarded as the end of the rod *h* is brought in contact with the lower end of the plunger *p*, and the latter is forced into the cylinder *s*, the air being compressed in the cylinder and forming a cushion, which prevents the too sudden arrest of the motion of the reservoir. The pressure of the spring *b* is such that when the steam is shut off from the apparatus, the valve C will be held firmly in its seat, so as not to be displaced by the movement of the reservoirs, if the latter are operated. When the steam is admitted to the apparatus, it passes through the opening *f*, and exerts a pressure against the under side of the valve C, and also passing into the opening or chamber *x*, exerts a pressure against the diaphragm *e*, and on the plunger *E*, forcing the latter downwards against the valve. The area of the end of the plunger *E* is precisely the same as that of the opening *d*, so that the pressure against the lower side of the valve will always equal that upon the top of the same, however the steam pressure in the boiler may vary. The valve C will, therefore, always turn freely in its seat, without danger of being lifted from the latter by the pressure of the steam. In some instances a weight may be substituted for one of the reservoirs, care being taken to so arrange the same that the leverage shall increase as the weight, or the remaining reservoir, descends.

I claim as my invention, and desire to secure by Letters Patent—

1. The valve C and steam-opening *d*, in combination with a plunger, *E*, which is caused to bear on the valve by the pressure of the steam, substantially as and for the purpose described.
2. The cylinder *s* and hollow plunger *p*, in combination with the reservoir H and rod *h*, with its piston *o*, the whole being constructed and operating as and for the purpose set forth.

In testimony whereof I have signed my name to this specification in the presence of two subscribing witnesses.

G. A. RIEDEL.
